UNITED STATES PATENT OFFICE.

THOMAS H. CLARK, OF DES MOINES, IOWA.

DESIGN FOR A DOUGH-ROUNDER.

59,621.

Specification for Design.

Patented Nov. 15, 1921.

Application filed November 26, 1920. Serial No. 426,651. Term of patent 7 years.

To all whom it may concern:

Be it known that I, THOMAS H. CLARK, a citizen of the United States, and a resident of Des Moines, in the county of Polk and State of Iowa, have invented a certain new, original, and ornamental Design for a Dough-Rounder, of which the following is a specification, reference being had to the accompanying drawing, forming part thereof.

The figure shows an elevation of a dough rounder embodying my invention.

I claim:

The ornamental design for a dough rounder, as shown.

Des Moines, Iowa, August 27, 1920.

THOMAS H. CLARK.
